[57] CLAIM

The ornamental design for harness for a radio cassette player, as shown and described.

DESCRIPTION

FIG. 1 is a front perspective view of a harness for a radio cassette player showing my new design;

FIG. 2 is front view thereof;

FIG. 3 is a right side view thereof;

FIG. 4 is a rear view thereof;

FIG. 5 is a left side view thereof;

FIG. 6 is a top plan view thereof;

FIG. 7 is a bottom plan view thereof; and,

FIG. 8 is a front view of a second embodiment of my design in which all parts of the second embodiment are the same as the first embodiment, except for the front.

The broken line showing of environment in FIG. 1 is for illustrative purposes only and forms no part of the claimed design.
